UNITED STATES PATENT OFFICE.

CHARLES PROSPER EUGÈNE SCHNEIDER, OF LE CREUSOT, AND EMILE RIMAILHO, OF NEUILLY-SUR-SEINE, FRANCE.

GUN-CARRIAGE FOR RECOILING GUNS.

No. 877,521.

Specification of Letters Patent.

Patented Jan. 28, 1908.

Application filed August 24, 1906. Serial No. 331,845.

To all whom it may concern:

Be it known that we, CHARLES PROSPER EUGÈNE SCHNEIDER and EMILE RIMAILHO, residing, respectively, at Le Creusot, (Saône-et-Loire,) France, and 54 Boulevard Maillot, Neuilly-sur-Seine, (Seine,) France, have invented new and useful Improvements in Gun-Carriages for Recoiling Guns, which is fully set forth in the following specification.

10 This invention has reference to a long-recoil gun carriage or mounting for firing at high angles of elevation and will be described in connection with the accompanying drawings, in which,

15 Figure 1 is a diagram of the usual appliances. Figs. 2 and 3 show in sectional elevation, and in partial plan respectively, an example of the application of the invention. Fig. 4 is a diagram of a second example of its 20 application.

A gun mounted upon a slideway which permits it to recoil for a long distance (more than a meter) could not readily operate at large angles of elevation (60°) if the trunnions were 25 placed in proximity to the center of gravity. In fact, with such angles it would be necessary, as shown in Fig. 1, in order that the breech *a* should not encounter the ground when it reaches *a'* at the end of the recoil, to considerably raise the trunnions *c* of the gun, which would result in giving the carriage *e* an inadmissible height.

In accordance with the present invention, the gun-trunnions *c* are arranged upon the 30 carriage *e* considerably beyond the center of gravity of the system comprised by the gun *b* and the slideway *d*. Assuming that this system *b*—*d* rotates around the axis *c*, it is 35 obvious that whatever the angle of elevation 40 may be, the breech *a* is able to make a long recoil between the cheeks of the carriage, without encountering the ground, and this without the necessity of raising the trunnions *c*, and consequently of increasing the 45 height of the gun carriage beyond that of existing carriages. Nevertheless, as the 50 weight of the gun-slideway system *b*—*d* is considerable, and owing to the fact that the center of gravity is situated largely in front 55 of the trunnions *c*, it would be difficult to raise the system in elevating the gun, and the invention therefore also comprises means for facilitating this operation. These means consist broadly, in an antagonistic or balancing device formed by a system of metal

springs, or pneumatic or hydropneumatic contrivances, which, are so supported on the gun carriage that they constantly exert upon the system constituted by the slideway and the gun, a tractive effort tending to raise this 60 system, the said effort being applied at a point on the slideway opposite to the center of gravity of the said system, relatively to the trunnions of the gun.

In the form of the invention illustrated by 65 Figs. 2 and 3, the slideway *d* may for this purpose be extended in the form of two arms *f* descending below the axis *c* into the space between the side cheeks of the gun carriage. In a cylinder *g* carried by the carriage there is 70 arranged between the trunnions *c* and the wheel-axle *h*, a spring *i* constantly tending to draw the arms *f* towards the wheel-axle. One extremity of this spring bears against the bottom of the cylinder, and its other extremity acts upon a piston *j*, the rod of which is coupled to a cross-piece *k* guided by rollers *m* in grooves *n* of the cheeks of the gun carriage. There are likewise coupled to this cross-piece, rods *o* to which chains *p* are attached. Each of these chains is also fixed to a point on a cam *q* keyed to a cross-piece *r* carried by the arms *f*; the said chains being wound upon the surface of the cams. The gun slideway system on the one hand, and 85 the antagonistic system on the other hand, may be arranged in equilibrium, like a balance, about the axis of the trunnions *c*.

The metal spring of the balancing device might be replaced either by a pneumatic 90 spring or by a pump body containing liquid already under pressure, or placed under pressure by means of a pump. In either case the antagonistic tension should be regulated in such a manner that its moment 95 relatively to the axis of the trunnions *c* is at all times equal to the value of the moment of the weight of the gun and of the slideway relatively to the said axis. The balanced gun-slideway system being capable 100 of ready change in elevation, any known elevating mechanism for effecting the changes may be employed, for example, a large toothed sector *s* pivoted to one of the trunnions *c* as center, and meshing with a pinion *t* carried by a spindle *u* on the gun carriage and with a pinion *v*, carried by a spindle *x* on an arm *y* of the slideway *d*. The balanced system above described is intended to apply 105 to a case in which the axis of displacement 110

about the gun trunnions is situated behind the center of gravity (the front being the muzzle of the gun). The said system is obviously applicable in a similar manner to cases in which it is necessary to displace the system about an axis otherwise arranged. Fig. 4 shows by way of example the system adapted to be displaced about a point at the muzzle of a gun mounted in a turret in which the embrasure *z* should be reduced to the minimum. In this example, the gun carriage *e* is assumed to be suspended from the roof of a turret or of a casemate. The said carriage is suspended from the roof by a pivot *1* and a segment *2* and is capable of movement about the vertical axis of the pivot. The slide-way system *b*—*d* is supported on the carriage *e* by trunnions *c* and the elevation of the system is effected by elevating mechanism in a manner similar to that already described in connection with that shown in relation to Fig. 2. In this arrangement, however, the counterbalancing piston of cylinder *g* is connected over a pulley *g'* to cam *q* in order that the slide system may be properly counterbalanced.

The axis of elevation formed by the trunnions *c* and constituting part of the slideway *d* is perpendicular to the axis of the pivot *1* and intersects it. It is at the meeting point of these two axes that the muzzle of the gun is situated, that is to say, the front extremity of the axis of the gun. The embrasure is

therefore reduced to the minimum around the pivot thus defined.

35

What I claim and desire to secure by Letters Patent of the United States is:—

1. In combination, a gun-carriage, a slide-way mounted thereon and having a gun sliding therein, said slideway being mounted to rock about an axis substantially beyond the center of gravity of said slideway system, a cam, and means for applying power through said cam to said slideway to counterbalance the weight of the slideway system in its different angular positions.

2. In combination, a gun carriage, a slide-way mounted thereon and having a gun sliding therein, said slideway being mounted to rock about an axis beyond the center of gravity of said slideway system, a piston-carrying cylinder mounted on said carriage, a cam on said slideway having a flexible connection with said piston, said piston acting through said connection on said cam to counterbalance the weight of the slideway system in its different angular positions.

In testimony whereof we have signed this specification in the presence of two subscribing witnesses.

CHARLES PROSPER EUGÈNE SCHNEIDER,
EMILE RIMAILHO.
